MULTICOLOR SHUTTLE CHANGING LOOM

Lewis S. Vose, Needham, Mass., assignor to
Crompton & Knowles Loom Works, Worcester,
Mass., a corporation of Massachusetts

Application April 4, 1932, Serial No. 603,051

15 Claims. (Cl. 139—227)

This is a continuation in part of my co-pending application Ser. No. 509,206, filed Jan. 16, 1931.

This invention relates to improvements in 5 multicolor shuttle changing looms and it is the general object of the invention to provide means whereby the multicolor shuttle changer principle may be applied to looms which normally come to rest to effect replenishment.

10 In multicolor weft replenishing looms there are usually employed two or more shuttles supplied with bobbins having differing wefts and a feeler mechanism is provided to determine the amount of weft remaining in the shuttles. A stack of 15 reserve shuttles is provided for each weaving shuttle which may be put in action, and it is an important object of my present invention to provide means to replace a depleted weaving shuttle with a reserve shuttle having the same 20 character of weft. This result may be accomplished through the action of a change or control shaft which operates shuttle advancing mechanism and is effective to present any selected shuttle from either of the stacks to a common position 25 preparatory to insertion in the shuttle box.

In a well-known form of single color changer a change shaft is employed having cams and operating connections which act while the loom is at rest to eject the empty shuttle and insert 30 a fresh shuttle in the shuttle box on the lay. It is a further important object of my present invention to employ certain of the mechanisms found in this known type of single color changer and to combine therewith other means all effective to produce a cycle of operations including a 35 selecting step to determine which reserve stacks shall supply the needed shuttle before the loom stops, coupled with other mechanism which operates to release the selected shuttle after the loom 40 stops.

If the shuttle should roll as it drops to the receiver box for depleted shuttles, the weft issuing from the delivery eye will wrap around the shuttle. The shed is normally open, and there 45 results a tensioning of the weft which will mar the finished fabric. It is a further object of my present invention to prevent a tight pick by providing means to clamp the thread prior to any operation on the part of the outgoing shuttle 50 which might act to tension the filling. This result I accomplish as set forth herein by means of a clamp controlled through the shuttle ejecting mechanism, the clamp operating to catch the thread before the depleted shuttle is expelled 55 from the shuttle box.

The shuttle magazine set forth hereinafter comprises a carrier to present the selected reserve shuttle to a conveyor which acts to move the selected shuttle into the shuttle box. It is a further object of my present invention to provide 5 means for moving both carrier and the conveyor toward the lay by a yielding force which may be arrested to prevent breakage in the event of a misplaced shuttle.

With these and other objects in view which 10 will appear as the description proceeds, my invention resides in the combination and arrangement of parts hereinafter described and set forth in the claims.

In the accompanying drawings, wherein a convenient embodiment of my invention is set forth,

Fig. 1 is a front elevation of certain portions of a shifting shuttle box loom with my invention applied thereto.

Fig. 2 is an end elevation of the feeler end of 20 the loom opposite the magazine,

Fig. 3 is an end elevation of the magazine end of the loom, parts being omitted,

Fig. 4 is an enlarged elevation of part of the structure shown in Fig. 3, some of the structure 25 being omitted for the sake of clearness,

Fig. 5 is a plan view taken in the direction of arrow 5, Fig. 1, on an enlarged scale,

Fig. 6 is an end elevation of the magazine viewed from the center of the loom, parts being 30 omitted,

Fig. 7 is a vertical section on a larger scale, on line 7—7 of Fig. 5,

Fig. 8 is a diagrammatic view showing the operating connections for the selector mechanism and 35 the carrier of the magazine;

Fig. 9 shows the means for actuating the selector mechanism from the box motion,

Fig. 10 is a horizontal section on line 10—10 of Fig. 6, showing the normal idle or resting position of the conveyor and carrier and the arrangement of the carrier to actuate the escapement devices,

Fig. 11 is a horizontal section on line 11—11, Fig. 6, showing the selector and escapement 45 devices in the act of delivering a shuttle from the rear magazine, parts being omitted,

Fig. 12 is a front elevation showing that part 50 of the feeler mechanism and including the electro-magnet and switch and the means to effect a change in the operation of the loom to initiate filling replenishment,

Fig. 13 is a plan view on an enlarged scale in the direction of arrow 13, Fig. 2,

Fig. 14 is a detail of the giveaway on the lock- 55

ing motion, being a vertical section on line 14—14, Fig. 13.

Fig. 15 is a front elevation of the knock-off device of the center filling motion,

5 Fig. 16 is an end elevation looking in the direction of arrow 16, Fig. 15 and also of the knock-off dagger on the lay,

10 Fig. 17 is a detail of the device to prevent transfer of a shuttle to the lay in case of non-ejection of the working shuttle, and

15 Fig. 18 shows the device for clamping the filling in its relation to other parts of the invention.

Referring to the drawings, I have shown a 15 breast beam 1, loom frame 2, and lay 3 pivoted at 4 and having swords 5. Shifting shuttle boxes 6 arranged to slide in guides 7 to bring either box cell level with race 8. Lifter rod 9 supports the boxes 6 and is actuated by a giveaway link 20 10, connected between the rod and box lever 11 moved by the box motion not shown. A change shaft 12 extends across the loom and performs the functions common to a similar shaft in the usual single color Stafford shuttle changing 25 mechanism, such as is shown and described in United States Letters Patent No. 1,100,886 granted June 23, 1919, to S. S. Jackson. In addition, however, shaft 12 does additional work not called for in former Stafford changers.

30 A filling feeler mechanism such as disclosed in my copending application Serial No. 593,814 acts to stop the loom upon deficiency of filling, and start rotation of shaft 12, one complete rotation of which effects weft replenishment and 35 starts the loom running again.

The lay 3 has a top horn 20 supporting two electric detector spring stressed needles 21 insulated from each other. A main control switch 22 on the loom frame has an arm 23, Fig. 12, 40 to be moved by the shipper handle 24 to open the switch when the loom is stopped for any reason. An electro-magnetic device 25 also on fixed structure acts when energized to lift a latch 26 (Fig. 2) normally below the path of a regularly moving actuator 27. The latter has a working forward stroke derived from cam 28 (Fig. 1) on the bottom or two-pick shaft 29 and preferably during the backward movement of the lay on which box shifting is completed. A battery 30 furnishes 45 electric power.

When the boxes shift upwardly the weft of the top shuttle is moved against the needles, and if weft be absent or substantially depleted the metallic ferrule of the bobbin will electrically connect the needles, whereupon current will flow in the following circuit: battery 30, wire 31, switch 22, wire 32, electro-magnetic device 25, wire 33, both needles and bare ferrule, wire 34 to ground, and back from ground to battery 30 by wire 35. This results in an effort to raise latch 26 (Fig. 2), but the working stroke of the actuator 27 is so timed that it passes the notch 36 of the latch before the boxes move far enough to close the previously traced circuit, hence the 60 latch is not moved on the backward movement of the lay when circuit is closed, but on the second backward movement thereafter. In this way assurance is given that control lever 37 is not rocked until the pick on which the empty shuttle 65 is picked out of the drop boxes and toward the magazine at the opposite end. On the next working stroke of the actuator, the latch will be engaged before the shifting of the boxes lowers the empty bobbin away from the feeler needles, 70 this relation maintaining the device 25 ener-

gized a sufficient length of time. The lower detector 38 operates in the same manner, the corresponding circuit closing through wires 39 and 40.

The net result of the previously described operation is to rock lever 31 (Fig. 2), thereby stopping 5 the loom and initiating a rotation of change shaft 12 by well-known means, such as shown in U. S. Patent No. 1,100,886.

The replenishing mechanism is located at the side of the loom opposite the detector and is 10 controlled by devices on and operated by the change shaft. A cam 45 (Fig. 3) on shaft 12 actuates a conveyor lever 46 through roll 47 on stud 48 mounted in slot 49 of said lever. Lever 46 is pivoted at 50 on the loom frame and a 15 spring 51 fastened to the frame acts on lever 46 at 52 to keep the roll in contact with the cam and draw said lever yieldingly toward the lay.

Box front 53 is raised by lifter 54 fulcrumed at 20 55 in stand 56 mounted on back of the lay through action of cam 57 on shaft 12 which actuates lever 58 connected to lifter 54 by connector 60 and fulcrumed at 61. When the front 53 is elevated to an extent sufficient to permit ejection 25 of a depleted shuttle, lifter 54 comes in contact with screw 62 in ejector lever 63, causing said lever to rock on shaft 64 mounted on lay carried stand 56, and move ejector 65 forward beneath binder 66 to push against the lower back portion 30 of the exhausted shuttle and eject it forwardly off the lay.

The outgoing shuttle falls down apron 67 toward catcher box 68, being held from dropping to the box bottom by plate 69. The latter is 35 fixed to a shaft 70 pivoted on the box and has mounted thereon a weighted lever 71 carrying a hook 72. Lever 71 is positioned so that as the conveyor lever 46 is moved forwardly at the beginning of replenishment, the hook will enter 40 notch 73 in said lever. By the weighting of the shaft 70 the hook will tend to enter the notch, but will be restrained from doing so if a shuttle is resting on plate 69. Lever 71 is held against 45 rocking under weight of the shuttle by engagement with a part of lever 46 when the latter is in normal forward position prior to its rearward movement incident to transfer. When the conveyor lever moves rearwardly it releases the lever 71 and the shuttle falls into the box. It 50 can be readily seen that if no shuttle is ejected from the lay the hook will enter the notch in conveyor lever upon preliminary forward movement thereof and restrain said lever from conveying a fresh shuttle to the lay, thereby preventing two working shuttles from being on the 55 lay at the same time.

A torsion spring 74 (Fig. 5) on shaft 64 operates on ejector lever 63 to restore it to normal position with stop 75 in contact with shaft 55 when lifter 54 descends. After shuttle ejection, the lifter descends until the ejector is withdrawn rearwardly to normal position, and a dwell portion of cam 57 holds front 53 at a distance above the shuttle race sufficient to permit entry into 65 the box of a replenished shuttle. Secured to the top of conveyor lever 46 (Fig. 3) by stud 76 is a conveyor 77 having two rear fingers 78, and a section 79 (Fig. 6) projecting above and substantially at right angles to the fingers to 70 form a shelf and back wall to support the shuttle when it is transferred to the lay. After the fresh shuttle has entered the shuttle box the lifter 54 completes its downward movement to engage and restrain forward motion of the shut- 75

tle, after which the conveyor 17 is withdrawn forwardly by the conveyor lever.

A cam 80 (Fig. 3) on shaft 12 engages a lever 81 fulcrumed at 61 and held against the cam by spring 82 between the frame and lever 81. As cam 80 turns it presents at the proper time raised portion 83 to lever 81, causing the top of the lever to move against collar 84 on a rod 85. Rearward movement of the rod rocks lever 86 fastened to shipper shaft 87 to restart the weaving instrumentalities of the loom.

The matter thus far described, except the shifting shuttle boxes, is substantially the same as that found in a well-known one color shuttle changer which stops to effect shuttle change.

In accordance with this invention, there is combined with this known structure a plurality of magazines one for each shifting shuttle box. There are shown two magazines 90 and 91 (Fig. 20) each made of three sections. A front inner section 92 of intermediate length and a short outer section 93 are both fixed upon the third rear long section 94 by bolts 95 (Fig. 1). The third section is bolted to the inner and outer magazine end frames 96 and 97 (Fig. 5), respectively, being provided with angular flanges 98 for the purpose. Thus the third sections serve to space and tie together the end walls or frames of the magazine.

The front sections of each magazine have their adjacent vertical edges spaced to define a thread slot, and the weft ends W and W' (Fig. 5) of the front and back reserve shuttles S and S', respectively, are led through their slots to a common thread holder 100 mounted on the inner frame 96. The delivery eyes D of the shuttles are preferably located adjacent to or in alignment with the thread slots, so that vibration of the reserve shuttles will not abrade the yarns. The rear section 94 of the front magazine, being continuous between the end frames, defines a passageway for the wefts W, thus preventing them from becoming entangled with the front shuttles or their wefts.

The inner magazine frame is mounted on the end of the breast beam, while the outer frame rests on a leg 101 (Fig. 1) extending up from the floor, and tie rods 102 (Fig. 5) help to hold the end frames in rigid and properly spaced relation.

Selector mechanism is employed to cause shuttle delivery to take place from the magazine corresponding to the depleted weaving shuttle. Accordingly, each magazine has a rock shaft 103 with control fingers 104 fastened thereto, see Fig. 7. The rockshafts are mounted in lugs on the rearward sides of the magazines, two fingers being used on each rockshaft. The fingers of each rockshaft are movable under the corresponding magazine to prevent delivery of the bottom shuttle from the magazine.

The fingers are so moved that delivery can take place from but one magazine at a time, namely, the one corresponding to the weaving shuttle to be ejected. This control is exercised by the box motion lever 11 as it rises and falls. A rock-shaft 106, see Figs. 1 and 9, journaled in angularly adjustable arms 107 on the loom frame, has secured thereto an arm 108 connected by link 109 to the box lever. At the magazine end the rockshaft carries an arm 110 (Fig. 8) having an adjustable connection with a rod head 111 on upwardly extending link 112. The latter connects with arm 113 fixed on the rear shaft 103. This last named shaft carries an arm 114 having

a pin and slot connection with a similar arm 115 on the front shaft 103.

Thus the shafts 103 are given equal but opposite angular movements each time the box rod 9 is moved to shift the boxes, and the delivery in turn is synchronously shifted from one magazine to the other. By reason of the slotted connections shown, the proper amount of motion for the fingers 104 can be derived from the box lever.

Escapement devices are provided in connection 10 with each magazine to release the bottom shuttle in each magazine and thereby permit selection by the fingers 104. These escapement devices also act to prevent escape of more than one shuttle at a time from the selected magazine. One such device is located at each end of each magazine, and each escapement comprises a pair of short vertical rock-shafts 116 (Figs. 10 and 11) journaled in bearings 117 on brackets 118 of end frames 96. Each shaft 116 has a shoulder seating on top of its bearing and has secured thereto a long lower arm 119 (Fig. 11) and a short upper arm 120 above the bearing. The arms are adjustable along their shafts to accommodate shuttles of varying heights, and angularly with respect to each other to adjust the time of escape of the shuttles.

The arms are so proportioned that when the end of the long arm 119 is normally under a shuttle to support a whole stack of shuttles the short arm will swing out of the path of descending shuttles, as shown in magazine 90, Fig. 11, but when the arms are in the position shown in magazines 91, Fig. 11, the bottom shuttle will be free to drop from the magazine, the short arms 35 acting to prevent descent of the shuttles above the bottom one which has thus been delivered. As the arms return to their normal position, the shuttle resting on the upper arms drops to the lower arms ready for the next operation. These 40 escapement devices, as stated, are located one at each end of each magazine and the arms of any pair are operated simultaneously, hence the shuttles are lowered in perfectly horizontal relation. The supporting ends of the arms are 45 broadened and reduced in thickness to facilitate their entry beneath the shuttles.

In order to transport a released shuttle to the previously described conveyor, I provide a carrier 121, see Fig. 10, having at each end a supporting portion 122, Fig. 4. Each of said portions slides freely in a slot or track 123, Fig. 7, formed on each magazine end frame, the tracks being inclined downwardly and rearwardly so that the path of the carrier will intercept the 55 arc of travel of the conveyor 46. By this arrangement there will be rapid divergence of the respective paths of the carrier and conveyor, permitting the latter to pass the carrier and assume a position nearer the front of the loom, from 60 which position the conveyor moves rearwardly to take the shuttle from the carrier.

The carrier 121 is common to all the magazines, the tracks being long enough to permit the necessary travel of the carrier. The latter is 65 provided with horizontal fingers 123a (Fig. 10) to receive a shuttle released from the selected magazine, these fingers being upturned at their front ends and bolted to the carrier with capacity for vertical adjustment on the carrier to arrange for 70 proper interception of the shuttle by the conveyor 17, see Fig. 10. End stops 124 are provided at each end of the carrier to limit lengthwise displacement of the shuttle at transfer.

To actuate the carrier the end of each portion 75

122 is equipped with a stud 125 (Fig. 6) extending through slot 123 in each magazine end frame. Each stud lies in a slot 127 in the lower end of an actuating lever 128 fixed on each end of a top shaft 129 pivoted in the top parts of the end frames. A crank 130 secured to the top shaft is pivotally connected to a link 131, (see Figs. 6 and 8) and reciprocated by a cam lever 132 (Fig. 8) pivoting about the fixed center 50. The cam lever is actuated downwardly by a cam 133 on the change shaft 12. This actuation of the carrier 121 under shuttle delivering magazines by the change shaft with the loom at rest is believed to be new in this type of loom. A spring 134 acts to hold the cam 133 and its cam lever in working relation, but permits the carrier to stop if obstructed in its rearward transferring movement. Adjustments of movements of the carrier and levers 128 are provided as suggested 20 in Fig. 8.

Through the use of the carrier as an intermediate transferring member, there is avoided the necessity of dropping the shuttles below the level of the breast beam in delivering them from the 25 magazines to the conveyor. The carrier and shuttles can therefore move over the breast beam and loomside and it is unnecessary to alter the relation between the frame and lay of existing looms. There is also avoided the need to drop 30 the shuttles through any great distance when delivering from the magazines, so that the chance of the delivered shuttle rebounding out of its desired position upon the carrier is reduced to a minimum. The magazines are arranged with 35 their bottoms at equal heights above the inclined path of the carrier, just enough space being left between such magazines with their selector devices and the carrier to permit rearward movement of a shuttle by the carrier.

40 While the carrier travels in a path inclined downwardly and rearwardly, it is to be noted that the supporting fingers 123a are slanted upwardly to cause the shuttle to settle back against the substantially vertical carrier abutment or 45 rear face 135 as the shuttle is borne rearward and downward. The fingers 18 on the conveyor are enabled to pass freely beneath the shuttle on the carrier without danger of their rearward extremities engaging with the shuttle bottom and 50 thrusting it off to escape from both transferring members.

The release of the bottom shuttle from the selected magazine and delivery to the carrier fingers 123a are both conveniently effected in the 55 present instance through the movement of the carrier itself. The carrier is formed at each end with a cam 136, Fig. 10, and these cams, in the forward travel of the carrier, engage rocker levers 137 fixed on the vertical shafts 116. As the 60 carrier moves forwardly from its normal rear position, the cams 136 rock the arms 119 and 120 to release the bottom shuttles of the magazines successively.

Springs 138 act to turn the vertical shafts 116 65 against the action of the cams 136. It will be seen, therefore, that forward movement of the carrier operates the escapement devices, but the selector fingers 104 permit delivery from one magazine only and prevent discharge of the bottom 70 shuttle of the other magazine.

The cam 133 (Fig. 8) is shaped to make the carrier pause a moment in its forward movement under each stack or magazine, to receive properly any shuttle which might fall to the carrier. 75 The cams 136 (Fig. 10) are long enough to hold

the arms 119 and 120 in releasing position during the full forward travel of the carrier to avoid releasing two shuttles from the selected magazine which might result at the rear magazine if the corresponding shafts 116 should oscillate twice. 5

After receiving the proper shuttle, the carrier moves rearwardly to a position slightly behind the conveyor in the simultaneous rearward travel of these two parts. In this connection, it is to be noted that the conveyor has a preliminary forward movement to clear the path of the carrier, and also to place the hook 12 to enter the notch 73 as already described. I wish it to be understood, however, that the conveyor can be so controlled as to rest normally in foremost position and start 10 to move rearwardly when the rear motion described herein occurs, without the small preliminary forward stroke. Thus, as the carrier is coming to rest the conveyor overtakes it and through 15 travelling in an intersecting path moves the shuttle off the fingers 123a through engagement of the shoulders 19 on the conveyor with the front side of the shuttle. The shuttle thereafter rests on the conveyor in the usual manner and is conveyed under the raised front wall 53 and into the shuttle box. The conveyor thereafter returns 20 forwardly to its normal resting position shown approximately in Fig. 8, and the carrier may remain in normal rearward position. 25

Upon completion of a replenishing cycle the 30 lever 81 moves rearwardly to start the loom and the weaving proceeds. The rockers 137 are free of the cams 136, and the shuttles in the several magazines remain supported by the long arms 119 until need again arises for replenishment. 35

As is customary on looms for fine fabrics, I employ a center filling stop motion of a well known type so that each pick can be detected. The lay has a stand 140 (Fig. 16) to which is pivoted a dagger 141 weighted so that its front 40 pointed end tends to rise. The fork has tines 142 movable about a lay carried pivot 143 and secured to a small rocking element 144. A link 145 connects the fork and dagger and a reciprocating rod 146 acts every pick to raise the fork. The 45 parts are so related that the dagger will be held down when weft is present, but will rise if weft be absent in the shed.

The shipper shaft 147 to which handle 24 is fixed has a finger 148 secured thereto and supporting a flat spring 149. A stand 150 on the breast beam supports a stub shaft 151 on which rocks a transmitting arm 152 lying just behind finger 148. A notch 153 in the arm is adapted to receive the dagger when raised as the lay advances. 50

A shield 154 is loosely pivoted on shaft 151 and when down covers the notch. A resetting rod 155 is arranged to engage the lay when the shield is in the down position shown in Fig. 16, and thus rock the shield back to normal non-shielding weaving condition as the lay advances after the loom has stopped. It should be noted that the dagger passes beyond the notch before the rod and lay coact to reset the shield, so that on the first pick after loom stoppage the stop motion is incapable of stopping the loom should filling be absent from the shed. This is a normal operation necessitated by the conditions growing out of the manual correction of a mispick. A spring 60 lock 156 yields to allow a hub 157 on the shield to rise, said spring thereafter retaining the shield 65 yieldingly raised. When the shipper shaft rocks counter-clockwise as viewed in Fig. 16, the spring 149 will overpower spring 156 and move the shield 70 75

down. The center stop motion is not new, and is set forth to illustrate a shielded type of motion such as found on certain looms.

This operation of the shield would permit the loom to restart after replenishment and continue running even though the last pick laid by the outgoing shuttle were defective, unless means were provided to prevent continued loom operation under these conditions.

10 The means which I employ herein to detect a mispick on the beat when weaving is resumed includes the usual side stop motion modified, if desired, as shown in the U. S. Patent No. 1,100,660 to Jackson, although the altered tines shown in 15 that patent need not be used, since the center stop motion shown herein will detect weft independently of the side motion.

Side stop motions are well understood, and I show parts of one herein for purposes of illustration in Figs. 1 and 5. The lay has a grid 160 along which the weft lies when the shuttle is boxed at the magazine side of the loom. A tiltable fork 161 is pivoted to a slide 162 mounted for back and forth motion on a guide 163 on the breast beam. A loop 164 formed as part of the fork extends forwardly to coact with an actuator head 165 having a regular forward motion on alternate picks when the shuttle is boxed on the adjacent end of the lay.

30 When weft extends across the grid, the fork is tilted and the head moves forwardly on an idle stroke. Should the weft be absent, however, the fork remains in position to permit the head to engage the loop, after which continued forward motion of the head will cause the slide to move forwardly. This results in movement of a knock-off lever 166 as will be understood by reference to Fig. 5 and there follows the customary movement of parts to stop the loom.

40 When the lay stops to replenish, the flat spring 149 on the shipper shaft lowers the shield to cover notch 153. When starting up after replenishment, therefore, the dagger 141, even though raised as a result of the defective pick, will be deflected away from the notch. The shield will be reset later in the forward beat of the lay, and it is during this interval that the side fork will operate to stop the loom. It is sufficient if the side fork operates only on replenishing beats of the lay, since the center motion detects every pick except the one when shuttle change occurs. Under the assumed conditions the lay will start up after replenishment, but will be stopped by the side fork.

50 Another feature of the invention relates to a 55 thread clamp to preserve the tension of the last pick laid by the expelled shuttle. In bobbin changers the outgoing bobbin leaves the weft in the shuttle eye, thereby preserving the tension 60 should the yarn unwind completely from the bobbin. Under similar circumstances in a shuttle changer, however, the yarn would pull out of the shuttle eye and the tension be lost.

To prevent this undesirable condition I form the 65 inner magazine frame with a rear arm 175 (Figs. 4 and 18) and pivot thereon a bell crank lever 176 as at 177. An arm 178 rigid with arm 128 rocks with the latter at replenishment. An adjustable pin and slot connection between arm 178 and 70 lever 176 moves the lower arm 179 of said lever. A clamp support 180 is pivoted to arm 179 at 181 and held yieldingly in the position shown in Fig. 4 by tension spring 182. Stops limit the amount of 75 relative motion of the parts about pivot 181 under spring action.

A retaining hook 183 pivoted to the frame is positioned by a stop 184 and is freely movable upwardly. The lower end of the support 180 has fixed and pivoted clamping blades 185 and 186, respectively. The movable blade has a depending actuating closing finger 187 and an upper opening lug 188.

Normally, the blades are in the closed position shown in Figs. 3 and 4, but at replenishment, with the lay at rest in rear position, the lever 128 will move forwardly as described to move the shuttle carrier forwardly. At the same time, the clamp support 180 will move rearwardly, causing the hook to open the frictionally retained movable blade to assume the position shown in Fig. 18. 15 This releases any previously received thread, and forms a notch 189 to receive the thread of the outgoing shuttle, which is later cut at the selvage.

Continued rear motion of the support causes finger 187 to strike the temporarily stationary lay 20 to return the movable blade to normal position relatively to the support, thereby clamping the thread of the outgoing shuttle.

As the shuttle carrier 121 moves rearwardly 25 with lever arm 128, the system of parts movable about pivot 177 returns to the normal forward position shown in Fig. 3, the hook camming up over the lug 188. If there be no thread for the clamp to grasp, the side stop motion will stop further weaving, but if weft be present and held 30 across the fork by the clamp, conditions are proper for continued weaving, and the temporary disability of the fork to detect because of the clamped thread will do no harm.

The carrier moves forwardly by a positive motion derived from its actuating cam and therefore moves the shuttle engaging wall positively in a direction away from the shuttle, so that any shuttle improperly delivered by the magazine will not be subject to a positive force. The rear motion of the carrier which advances the shuttle engaging wall 135 (Fig. 7) toward a shuttle is resilient or yielding, so that a misplaced shuttle will be able to arrest rearward movement of the wall and carrier and avoid damage.

45 The thread clamp shown in Figs. 3 and 4 is not claimed herein but forms the subject matter of my Patent No. 2,004,681, issued June 11, 1935.

Having thus described my invention it will be seen that changes and modifications may be made 50 therein by those skilled in the art without departing from the spirit and scope of the invention and I do not wish to be limited to the details herein disclosed, but what I claim is:

1. In a multicolor shuttle changing loom having a lay and a shuttle, a plurality of stacks of reserve shuttles, discharge means to eject a depleted shuttle from the lay, a carrier common to all of said stacks of shuttles and operable simultaneously with said discharge means to advance 60 a selected reserve shuttle from the stack corresponding to the active shuttle rearwardly toward the lay, a conveyor to transfer a selected shuttle from the carrier to the lay, and means to prevent operation of the conveyor to move the selected 65 shuttle to the lay if the discharge means fails to eject the depleted shuttle from the lay.

2. In a multicolor shuttle changing loom having a lay and a shuttle, a plurality of stacks of reserve shuttles, discharge means to eject the depleted shuttle from the lay, a carrier common to all of said stacks of shuttles and operable simultaneously with said discharge means to advance 70 a selected reserve shuttle from the stack corresponding to the depleted shuttle rearwardly to 75

- ward the lay, a conveyor operable subsequently to the movement of the discharge means and carrier to transfer the selected shuttle from the carrier to the lay, and means to prevent operation of the conveyor if the discharge means fails to eject the depleted shuttle.
3. A loom having in combination, a lay, a shuttle box in active picking position on the lay, reserve shuttle magazines, means to effect delivery of a reserve shuttle from a selected magazine, a movable carrier to receive a selected reserve shuttle, and a conveyor movable to transfer the selected weft supply from the carrier in a substantially horizontal direction into the shuttle box.
4. A loom having in combination, a lay, a shuttle box in active picking position on the lay, reserve shuttle magazines, means for selecting the magazine next to effect delivery of a shuttle, means for effecting delivery of a shuttle from such selected magazine, a carrier to receive and advance such shuttle, and a conveyor adapted to transfer the shuttle from the carrier into said shuttle box, said conveyor effective to move the shuttle in the same general direction in which said shuttle is advanced by the carrier.
5. In a shuttle changing loom having a lay which remains at rest in rear position during the shuttle changing operation, a shuttle box on the lay, a plurality of groups of reserve shuttles arranged in front of the lay, the depleted shuttle movable from the lay at rest toward the reserve shuttles, and means to move a shuttle from under any selected group into the shuttle box along a path the major component of which is horizontal, said means including two devices one of which moves under the groups to engage and deliver a shuttle to be changed to the other device, said other device movable rearwardly from the groups toward the lay to place the shuttle into the shuttle box.
6. A loom having in combination a lay, a shuttle box in active picking position on the lay, reserve shuttle magazines, a conveyor adapted to transfer shuttle directly into the shuttle box, a carrier receiving the reserve shuttle from the magazines and delivering it to the conveyor, and devices in connection with the magazines to effect delivery of a reserve shuttle therefrom, actuated by the carrier after the latter is called into action.
7. A loom having in combination, a lay, stationary reserve shuttle magazines, transferring means acting to advance a reserve shuttle from one of the magazines toward the lay, devices in connection with each magazine actuated by the means tending to effect delivery of a reserve shuttle from each magazine, and selector mechanism preventing delivery of a weft supply from all but one of the magazines, said transferring means common to the reserve shuttle magazines.
8. A loom having, in combination, a lay, stationary reserve shuttle magazines, means for advancing a reserve shuttle from any one of the magazines toward the lay, escapement devices tending to effect delivery of a shuttle from each magazine whenever transfer to the lay is to be effected, and means actuated independently of the escapement devices to determine from which magazine delivery of a weft carrier is to be effected.
9. A loom having in combination a lay, a plurality of stationary reserve shuttle magazines, an escapement device for each magazine for delivering one shuttle at a time, selector mechanism effective to limit delivery from but one magazine
- at a time; and means common to the magazines for advancing a shuttle from any magazine toward the lay, said means including an element which successively actuates all of said escapement devices to effect delivery of a shuttle from the selected magazine and thereafter carry the released shuttle to the lay.
10. In a multicolor shuttle changing loom having a lay, a plurality of magazines for reserve shuttles, a carrier having a shuttle receiving stroke away from the lay to receive shuttles delivered by the magazines, and said carrier having a shuttle delivery stroke toward the lay, and means to cause a dwell of the carrier on its receiving stroke as it reaches each magazine, sufficient to permit a released shuttle to drop by gravity onto said carrier.
11. In a multicolor shuttle changing loom having a lay, a plurality of reserve shuttle magazines, a carrier having a shuttle receiving stroke with respect to all of the magazines at the time of replenishment, a shuttle moving wall forming part of the carrier, means to move the carrier positively in a direction to move the wall away from the shuttle that is dropped from any of the magazines and to cause a dwell in the movement of the carrier as the latter reaches each magazine on its shuttle-receiving stroke, sufficient to permit a released shuttle to drop by gravity onto said carrier, and means to thereafter move the carrier yieldingly in the opposite direction and to thereby move the wall against any shuttle dropped by the magazines and propel such a shuttle toward the lay.
12. In a multicolor shuttle changing loom having a lay, a plurality of reserve shuttle magazines, reserve shuttle release mechanism for the magazines, a carrier having a receiving stroke under all of the magazines at the time of replenishment to actuate the release mechanism and receive a shuttle released from any magazine, and means to cause a dwell of the carrier as it reaches each magazine in its receiving stroke sufficient to permit a released shuttle to drop by gravity onto said carrier.
13. In a multicolor shuttle changing loom having a lay provided with a shuttle box, a plurality of stacks of reserve shuttles in front of the lay, means to expel a depleted shuttle from the shuttle box forwardly of and away from the lay toward said stacks, and a pair of devices to move a shuttle from under any stack to the shuttle box, one of said devices being common to all of said stacks and operable during operation of said expelling means to move a shuttle from under any stack rearwardly to the other device without crossing the path of the expelled shuttle, and said other device thereafter moving the shuttle along part of the path of the expelled depleted shuttle into the shuttle box after the depleted shuttle has been expelled from the lay.
14. In a shuttle changing loom having a lay, a single shuttle box permanently in picking position relatively to the lay, a plurality of stacks of reserve shuttles, and means to move a shuttle from under any stack to the shuttle box along a path the major component of which is horizontal, said means including two separate shuttle moving devices each of which engages and moves the selected shuttle rearwardly, one device moving the shuttle being changed into a position from which the other device conveys the shuttle into the shuttle box the said shuttle being changed being in picking position relatively to the lay as

soon as said shuttle enters the box because of the position of the latter on the lay.

15. A loom having, in combination, a lay, a shuttle box on the lay permanently in picking position relative to the lay, a plurality of vertical reserve shuttle magazines mounted side by side, mechanism to release a single selected reserve shuttle at a time from the magazines, means common to all of said magazines for advancing a re-

leased shuttle from the magazines toward the shuttle box on the lay, said means being moved successively under said magazines to receive a shuttle released by said release mechanism, and means to effect delivery of said selected shuttle direct to the shuttle box, the selected shuttle being in picking position on the lay when positioned in said shuttle box. 5
